APPARATUS FOR PROJECTING CINEMATO-
GRAPHIC IMAGES CARRIED ON DISKS

Rudolf Levy, Berlin-Halensee, Germany

Application September 22, 1936, Serial No. 101,919
In Germany May 17, 1932

4 Claims. (Cl. 88—16.2)

The invention relates to a projecting apparatus for disk-shaped cinematograph records carrying images, which are arranged in one or more spirals and which are made to appear to stand 5 still optically by means of instantaneous illumination, while the disk rotates uninterruptedly, especially in combination with sound reproducers.

In accordance with the invention, with such 10 a projector for image disks, particularly for the purpose of making possible a construction of the projecting device similar to that of a phonograph, with objective projection of the cinematographic images, use is made of an image illuminating device which is known per se, which consists of one or more illuminating tubes, through 15 which electric condensers are rapidly discharged. By the term "illuminating tubes" there is to be understood here an electric discharge lamp which serves for emitting light, and which may be filled 20 with one or more gases or vapors or with a mixture of gas and vapor. If necessary the discharge lamp may also be provided with substances which, for example, produce fluorescence under 25 the influence of the luminous discharge, particularly by means of the short wave length components thereof, which substances, however, are not appreciably phosphorescent, that is, which do not remain luminous for any appreciable time 30 after the excitation ceases, which may cooperate with the luminous discharge. The luminous tube may have heated or liquid electrodes and auxiliary devices for starting, of the well known types.

By the present invention numerous constructional difficulties occurring in the projection of 35 spiral image-series disks are eliminated, for in accordance with the invention the construction becomes surprisingly simple and easy to operate; phonograph-like projecting apparatus of restricted 40 dimensions and relatively low weight are made possible, which permit again reviving the older method, severely criticised and finally abandoned in favor of the film strip, namely, the use of a disk-like carrier of a cinematogram with numerous 45 rows of very small pictures and accompanying sound records, and thereby for the first time the many advantages of such an image disk become available in full and for general use.

A synchronization of the image succession and 50 the condenser discharge is very easy to attain. Because of the characteristic of the device according to the invention which combines the source of illumination and the equalizing element in one, there is absolutely no disturbance 55 produced, for example, by the moving of the disk

or the receiving element transverse to the direction of motion of the series of images or the non-rectilinear travel of the image. This is a very material advantage over the already known complicated mechanical constructions wherein a complicated mechanical connection together with drive gears was interposed between the driving element and the image equalizing element, which may be the cause of frequent failure during the exhibition.

The discharge of the condenser through the luminous tube takes place extremely rapidly, and because of the brevity of the current impulses instantaneous maximum current values may be attained which are a multiple of the current values permissible in normal operation without improperly increasing the effective load on the discharge lamp, because not the total load of the tube but primarily the current density in the discharge gap is determinative of the efficiency 20 of the tube. Thus because of the shortness of the light flashes very sharp projection images may be obtained and because of the high instantaneous current densities also extremely bright projection images are obtained which are amply sufficient for home use.

The speed of rotation of the spiral image disk, in accordance with the invention may depend upon the discharge frequency of the illuminating device which is constructed as a complete condenser trip switching means. The flashes of light produced in the luminous tube hereby serve not only for illuminating the images to be projected at any instant, but, furthermore, also for influencing a photoelectric cell, the current impulses of which, produced by the flashes of light, if necessary after suitable amplification, are conducted to a synchronizing device which controls the speed of rotation of the image disk.

If all the images of the spiral image disk have 40 the same linear spacing from one another, then by suitable setting of the magnitude of the synchronizing moment which is produced in the synchronizing device controlling the drive means of the image disk, the speed of rotation of the image spiral disk is given a supplemental increase or decrease, because upon similar spacing of the images from one another, the angular velocity of the rotating image disk must be continually 45 varied.

For setting the desired frequency of image changes, comparison standards may be provided, for example, a tuning fork to be observed in the intermittent light of the illuminating tube.

The moment of tripping the condenser and 55

thereby likewise the starting of the luminous tube may also be controlled by independent means. The discharge of the condenser may then, for example, be controlled, by movable apparatus elements, which are mechanically or electrically connected with the driving means of the apparatus. The synchronizing of the moment of tripping of the condenser may, for example, be produced by a frequency creator, for example, by a revolving generator depending upon inductive effect, or by a contact breaker connected and disconnected by an auxiliary current source which is mechanically connected with the driving mechanism of the image disk or by a special synchronous motor, if necessary with a different number of poles, which preferably is driven from the same alternating current power system.

The generator which produces the synchronizing frequencies may also be independent of the projection apparatus, and, for example, may consist of a separately driven tuning fork interrupter or vacuum tube generator, which provides the controlling power for synchronizing the driving and/or light flash frequency.

25 The condenser tripping moment and the drive moment may further be controlled directly from the same alternating current supply system, for example through a transformer or indirectly, for example, through a frequency converter.

30 In such cases where the images are arranged at equal angular intervals from one another and lie in radial rows, at any time an entire radial row of the images may be illuminated in common, whereby, however, at such time only a single 35 image of this series is actually used. The illumination then takes place preferably through a cylindrical lens which is arranged between the luminous tube and the image plate. This illuminating device may then be stationary, and structurally 40 separate from the radially shiftable optical projection parts. In this case thus the projection elements are the only portion which is to be moved during the projection namely, the radially shiftable portion.

45 The image spiral disk itself may serve as the rotor of the synchronizing frequency generator. For this purpose there may be provided upon the edge of the image spiral disk or upon the disk itself or upon a special preferably co-axial auxiliary carrier or upon a sound disk connected thereto, control frequency records, for example transparent or reflecting marks, such as slots, which are illuminated by a special lamp, whereby the transmitted or reflected intermittent light 50 falls upon a photoelectric cell which preferably controls the tripping charge of the condenser through an amplifying means. In order to make possible an exact setting of the images it is advantageous to project the image of the slit at a 55 material optical enlargement upon the photoelectric cell.

The luminous tube preferably contains an auxiliary control electrode upon which a retarding potential may be applied and which is 60 connected to an interrupter. This interrupter may consist for example of a rotor which has a metallic surface provided with insulating slots, with which cooperates a sliding spring contact connected with the auxiliary electrode.

70 For obtaining a concentrated light effect the luminous tube may be rolled together screw-fashion and is preferably arranged in a special evacuated container. This container is preferably formed as a reflector.

75 For keying the image records a fork-like de-

vice which is shiftable or oscillatable, or an oscillatable portion, may serve, one of which, for example, an arm arranged beneath the image disk, carries the illuminating device or the optical projection elements, whereas upon or in the other, for example, the arm arranged above the image disk, is provided with the optical projection elements or the luminous tube. This fork-like keying device must be shifted or swung laterally during the projecting, which is preferably 10 accomplished by a keying rod which engages in a spiral groove of the image disk. It is advantageous to assist this lateral motion through an additional radially acting force, for example, by means of a weight, a spring or the like. The arm 15 arranged above the spiral image disk is preferably so constructed that it makes possible a ready interchanging of the image disk. The optical projection parts may be adjustable along their optical axis as well as parallel to the plane of 20 the image disk.

Preferably all the illuminating and keying devices are provided in a swingable arm above the image disk.

In order to attain as nearly correct as possible 25 a projection of the images it is preferable to provide upon the underside of the rim of the image disk a supporting bearing, constructed for example as a ball or roller bearing.

In such cases where the sound record disk is 30 structurally separate from the image disk, said two disks may be arranged adjacent one another and each manipulated by a separate swingably arranged arm. It is, however, also possible to arrange the two disks in different planes 35 rotatably arranged above one another at a definite location and to drive them in common by a single motor in such way that the image disk rotates more slowly than the sound disk. Finally, it is also possible to drive the two disks by separate 40 synchronous motors having different numbers of poles, which are connected to the same alternating current supply system.

If the images are not transparent, then the image projector may consist of a structural unit 45 which is shiftable above the image disk upon a radial arm which is foldable upwardly and which contains the luminous tube, the condenser, the optical condensing system and the projection objective. It is, however, also possible to provide 50 for the manipulation of the images through a swingable arm in the interior of which are arranged the illuminating tube, the optical condenser and the projection objective. The condenser in this event may advantageously be arranged in the axis of swing of the image selecting arm. The illuminating tube may also be arranged in the axis of rotation of the swinging arm and may be so constructed that it may radiate its light in an axial direction, namely, upwardly. In this axis of rotation, according to the invention, above the illuminating tube there is provided a reflector which deviates the light in the direction of the arm, for example, a prism, mirror or the like. In using opaque images the 55 projecting optical system may be arranged in the free end of the swinging arm.

All the electrical devices are preferably screened externally by a metal housing. In accordance with the invention a light shutter is provided 70 upon the container enclosing the illuminating tube or in the light-conducting swinging arm which may be opened temporarily for the purpose of adjusting the image selecting device.

A switch, which disconnects the source of 75

- charging current from the condenser, may be so constructed and arranged that simultaneously with the disconnecting of the charging current it connects a resistance in parallel with the condenser, whereby any possible residual charges of the condenser may be dissipated through the resistance, in order, for example, on changing the illuminating tube, to protect the hand of the operator from danger of shock.
- 10 It is advantageous to project the pictures upon the opening of the loud speaker of a radio receiver which amplifies the sound and is manipulated synchronously with the picture and provided with a suitable projection receiving surface.
- 15 Individual points of the image disks may be provided with synchronizing symbols which correspond to similar marks upon the inner or outer edge of the image disk, or an annularly arranged legend may be provided which refers to the subject matter of the images.
- 20 In the drawings examples of the invention are illustrated and in said drawings:
- Fig. 1 shows an image spiral record disk wherein in the spacing of the individual images from one another is constant.
- 25 Fig. 2 is another example of an image spiral record disk wherein the images are arranged in radial rows, wherein thus the angular velocity of the rotating plate is constant.
- 30 Fig. 3 is a diagrammatic representation of a projecting means for the recorded images.
- Figs. 3a and 3b show two different views of a source of light serving for illuminating the recorded images.
- 35 Figs. 4, 4a, 5, 5a, and 6 are further examples of a projecting device.
- Fig. 7 is an external elevation of a projecting device for opaque images wherein the sound record disk is arranged concentrically to the image spiral record disk.
- 40 Fig. 8 is a detail of the embodiment according to Fig. 7.
- Fig. 9 is the keying or selector means of the example according to Fig. 7 on an enlarged scale.
- 45 Fig. 10 is a further example of an embodiment wherein the keying of transparent images is accomplished by a swinging fork.
- Fig. 11 is a further example of an embodiment of a keying arm for the opaque image spiral recorded upon the disk.
- 50 Fig. 12 is a complete projecting and reproducing device, wherein the image spiral record disk and the sound record disk are arranged adjacent one another and
- 55 Fig. 13 is a projecting and reproducing apparatus wherein the sound record disk is arranged above the image disk.
- 60 Figs. 1 and 2 show two different embodiments of an image record disk known per se, with a spiral type of arrangement of the individual images.
- In Fig. 1 the individual images 2 are arranged upon a circular plate in the form of spiral turns 1, which mutually have a uniform linear spacing 4, from one another. The plate has in the manner known per se a central opening 3 whereby the plate is pushed over the central pin of a turn table just as with the customary phonograph records. The playing of the plate occurs with 65 a speed of revolution which remains linearly constant, that is, with a variable angular velocity of the rotating image record carrier.
- In Fig. 2 the series of pictures are likewise arranged in spiral turns, however, here the arrangement of the individual images 5 is in radial 70 rows in such manner that all the images 5 have the same angular spacing from one another. By this arrangement of the images there is, of course, produced a less efficient utilization of the space than in the plate according to Fig. 1, it has, 75 however, the advantage that the turn table may rotate continuously at constant speed like an ordinary sound record turn table. For the purpose of keying by means of a swinging arm the individual images 5 lying in the radial series may also be located adjacent one another in arcuate curved lines.
- The plate according to Fig. 1, as well as that of Fig. 2 may in the known manner be mounted and driven from the rim instead of from the center point. The keying in both plates takes place in that the keying element or the rotating image disks are continuously shifted radially during the projection.
- Fig. 3 shows diagrammatically a projecting device for image spiral disks wherein the illumination device also controls the driving of the image disk.
- Here 6 designates a luminous tube the electrodes of which are connected with the terminals 7 and 8. The luminous tube is helically wound in order that the light radiation may be concentrated into as small a space as possible. The rolled-up luminous tube is here arranged within a housing 9 which is transparent only at the exit points for the light, the remainder, however, being constructed as a reflector (see Figs. 3a and 3b wherein the luminous tube is shown in elevation and in plan). Preferably, particularly for attaining or maintaining suitable temperature conditions, the housing 9 may be evacuated. In the drawings the luminous tube lamp 6, 9 has a screw base 10 of known type, whereby the lamp may be screwed into an ordinary lamp socket.
- The luminous tube 6 is fed from a condenser 40 11, which is relatively slowly charged through a resistance 12 by means of direct current or rectified current. Upon attaining the break-down potential the condenser 11 suddenly discharges through the luminous tube 6, whereby this discharge proceeds to a point below the extinction potential. By this rapidly occurring flow of current of great current density an intense flash of light of very short duration is produced by the tube 6, which acts on the one hand through an 45 optical condenser system 13 upon the image spiral disk 14 and acts on the other hand upon a photo-electric cell 15. The current impulses produced by the illumination of the cell 15 are preferably conveyed to the stator 17 of the synchronizing device through an amplifier 16. The stator 17 acts upon a pole wheel or rotor 18, which is secured to the shaft 19 of the turn table, which carries the transparent image record table 20, upon which the image-spiral record disk 14 is 50 placed. By suitable proportioning of the charge voltage, and dimensioning of the likewise adjustable charging resistance 12 and of the condenser 11, any desired frequency may be attained. The number of flashes per second may, for example, 55 also be varied by adjustable discharge gaps (spark gaps) or by connecting devices for short circuiting or shunting partial discharge gaps. Upon using spark gaps, if desired, the light of the spark may also be used to cooperate in illuminating the image. The potential of the charge may be increased in known manner by automatic series connection of parallel-connected condensers.
- The synchronizing moment which produces 70 each discharge of the condenser 11 through the 75

luminous tube 6 by means of the photo-electric cell 15 in the synchronizing device 17, 18 is, for example, by suitable dimensioning of the amplifier 16, selected to be of such magnitude that with a constant linear separation of the images (in accordance with Fig. 1) a supplemental acceleration or braking of the speed of rotation of the synchronous driving motor may be accomplished. If, however, the images 21 have equal angular spacings (according to Fig. 2), that is, if they are arranged in radial strips, then the synchronizing device, 17, 18, will produce a constant speed of rotation of the disc turn table 20.

The acceleration or braking of the speed of rotation may be accomplished by spatial phase shifting of the rotating synchronizing elements. The phase shifting may take place stepwise whereby the magnitude of the steps is very closely related to the number of images in the circumference of one turn of the spiral.

The securing of the desired discharge frequency, that is, of image change frequency, may be accomplished or controlled by means of customary mechanical or electrical revolution counters or also by means of comparison standards. As a comparison standard, for example, a tuning fork with graduations may be employed whose oscillations are observed stroboscopically in the intermittent light of the luminous tube 6. A still projection of individual partial images may also be attained with the arrangement according to Fig. 3 by optically screening the photo-electric cell 15 from the luminous tube 6 or by disconnecting the amplifier 16. The illumination of the individual image which is to be projected then takes place through the light flashes produced by the condenser discharges.

The luminous tube 6 and the photo-electric cell 15, together with the optical condenser 13 are arranged in a common housing, which may consist of metal and, for example, may be grounded to secure electrical shielding. This is of particular importance when there are any electrical sound receivers in the vicinity.

Opposite the luminous tube 6 is arranged the optical projection system 23, above the image disk. A fork-shaped holder 26, to the lower arm 24 of which is secured the luminous tube 6 and on the upper arm 25 of which is arranged the optical projection system, serves for securing both parts. In the example illustrated in the drawings it is assumed that the fork is to be moved radially with respect to the image disk 14 and, for example, from the inside toward the outside. A preferably replaceable guide pin 27 is provided on the optical projection system 23, and is guided in a spiral groove 28 of the image disc, whereby during the rotation of the image disc 14 it shifts laterally both the optical projection system 23 and the lamp 6. The two arms 24 and 25 thereupon slide in guides 29 and 30, which are provided in a mounting 31. Preferably the radial moving of the fork 26 is assisted by a force acting in the same direction, produced, for example, by means of a spring or a weight 34, which is secured to a cord 32, which is passed over a guide roller 33. Hereby also any existing play in the guide groove is made harmless, whereby swinging of the guide pin in the spiral groove is prevented.

The optical projection system is preferably adjustable not only in the direction of its optical axis but also parallel to the plane of the image disk, with respect to the series of images. For this purpose it may be mounted shiftably and securely upon a small sliding carriage. The upper

arm 25 of the fork 26 consists of the two parts 25a and 25b which are so connected with one another by a hinge 35 that the arm 25a may be folded up with the optical system 23 for the purpose of ready changing of the image disk. A handle 36 is provided for facilitating the folding-up.

It is, however, possible to so arrange the connecting element 26 or the bearing block 31 that they may swing laterally. This is of particular importance when the fork is not to be shifted radially rectilinearly, but, like the tone-arm of a phonograph, is to have a swinging motion during operation.

A slot 38 serves for guiding the optical condenser 13 in the mechanism housing 37. The housing 22 in that case may slide upon a special rail 38a. The portion 26 emerging from the mechanism housing 37 during the projection may be covered like the parts 32, 33 and 34, in order to protect these parts against any external influence. Preferably the turn table 20 is provided at its outer rim with guiding bearings 37a, for example rolls or balls, in such manner that the rim of the turn table is supported upon the plate 25 of the mechanism, in order to prevent a striking of the turn table 20.

In the example according to Fig. 4, the tripping impulse of the condenser is controlled by means of movable apparatus parts, which are in mechanical connection with the device. Direct current is fed to the binding posts 39 and 40, which charges the condenser 42 through the resistance 41. The luminous tube 43 is connected in parallel with the condenser 42 and has the main electrodes 44 and 45 and also an auxiliary electrode 46. The electrodes 44 and 45 obtain their potential difference from the condenser 42. The auxiliary electrode 46 is, for example, in the form of a grid and is connected with an auxiliary battery 49 through brushes 48 and 52 sliding upon an interrupter disk 47 (c. f. also Fig. 4a). The interrupter disk 49, as may be seen from Fig. 4a, consists of insulating material and is provided on both sides with a common metallic coating 50 having radial apertures 51. The number of the apertures 51 corresponds to the number of images in one series in the circumference of a turn of the spiral, whereby it is here assumed that the images are at equal angular spacing 50 from one another.

The auxiliary potential of the battery 49 prevents the starting of the luminous tube 43 when the condenser is completely or nearly completely charged. If this auxiliary potential is removed by the apertures 51 then the retarding potential existing upon the grid 46 is eliminated, so that starting can now take place, whereby the condenser discharges instantaneously through the luminous tube 43, producing a very brief but very bright flash of light. By means of an optical condenser 53 the image spiral 54 upon the plate 55 is illuminated. The plate 55 rests upon a transparent turn table 56, for example made completely or partially of glass, and is secured thereto by means of one or more spring clamps 57 at the rim. The image spiral disk 55 or the turn table 56 and the interrupter disk 47 are secured to a common shaft 58.

In the example according to Fig. 5 the discharge of the condenser is likewise controlled by means of movable mechanical elements. The image spiral disk 59 here lies upon a turn table 60 and is provided at its rim with a number of transparent slots 62 (see also Fig. 5a). In place 75

of the slots, light-absorbing or light-reflecting coatings may be provided, for example printed black and white indicia. The image series here also are spaced at equal angular intervals from 5 one another, whereby there corresponds to each radial series of images 63, one slot or one light-reflecting or light-absorbing coating. The arrangement may, however, also be such that there corresponds to each individual image one 10 parent or reflecting mark. The slots 62 may be copied simultaneously with the printing of the images upon the plate 59 or they may also consist of corresponding apertures in the plate. Instead of being arranged directly upon the image 15 plate 59, one or more marks may also be arranged upon a special, rapidly rotating carrier, for example, upon a disk or the like which is connected with the turn table. For example, this carrier may be arranged upon the shaft of a 20 phonograph turn table connected therewith; also this sound record may have a control frequency designation arranged thereon, for example upon its rim. If the sound record carries a plastic sound record, then preferably, there may likewise be at its rim a plastic control frequency 25 record arranged in a closed curve, which is reproduced by a special reproducing device.

Beside the spiral series of images there is a 30 guide path 74. A constant source of light 64 whose light rays are combined into a pencil by an optical system 65, illuminates the marks 62 through a diaphragm 66 when passing said marks. Thereby, by means of the optical system 67 and the mirrors 68, 69 and 70 it produces upon 35 a screen 71, which is provided with a slot 72, flashes of light which fall upon a photo-electric cell 73. The electrical impulses produced by these light impulses hereby serve in known manner, if necessary through an amplifier 75, for synchronizing the illuminating device of the present invention, in that they, for example, are fed to the grid of a gas-filled discharge bulb (Thyratron), which in turn controls in known manner the starting of the luminous tube which illuminates 40 the image spiral disk 59 and the discharge of a condenser through the tube. In case the control electrode of the Thyratron has a photo-electrically active coating, the light impulses passing through the slot 72 may strike directly upon said 45 coating. The long projection path obtained by the mirrors 68, 69 and 70, provides a considerable magnification of the image of the slot 62 upon the slot 72, preferably arranged in the direction of the slot image and adjustable parallel thereof, to, whereby the setting of exact starting points of the condenser discharges and thereby of the image stroke are readily made possible.

In the embodiment according to Fig. 6 the condenser discharge and the drive motor are 50 controlled by the same alternating current supply system. The luminous tube 76, which is shown in the drawing as a mercury vapor lamp and which may be arranged in a housing provided with a reflector, has a solid electrode 77 and a mercury electrode 78. In parallel to this tube 55 is arranged a condenser 79 which is charged through the resistance 80 from a direct current source, by means of the binding posts 81 and 82. The voltage at the condenser is so chosen that 60 starting of the luminous tube cannot yet take 70 place.

The alternating current supply potential conducted to the terminals 83 and 84 actuates, on the one hand, the driving motor 85 preferably 75 constructed as a synchronous motor and, on the

other hand, produces through the transformer 86, potential impulses which by means of the external coating 87 produce in well known way 5 an ignition point upon the mercury cathode 78 and in this way start the discharge of the condenser 79 through the luminous tube 76. The synchronous motor 85 provides the driving of, or corrects the synchronous drive of, the shaft 88, which carries the turn table 89 and the image disk 90.

In case the frequency of the alternating current supply is not suitable, it is possible by frequency multiplication or demultiplication of the supply frequency to provide the necessary control frequencies in well known ways. Of course, 15 a suitable conversion device may also be connected if necessary between the drive motor 85 and the shaft 88. The charging of the condenser 79 may likewise take place from an alternating current supply system, namely, through a rectifier. 20

The discharge current of the condenser passing for a brief time between the electrodes 77 and 78 of the luminous tube provides a very brief but very bright flash of light which by means of a cylindrical lens optical system 91 is 25 thrown in the form of a strip upon a radial image series (c. f. for example, Pos. 63 in Fig. 5a). All the single images lying in one radial series are thus simultaneously illuminated, whereby in accordance with the operation at any moment only 30 one single image of this series is utilized.

This has the advantage that the light source need not, for example, as in the embodiment of Fig. 3, be shifted radially, but may be arranged 35 stationarily. Hereby the projecting apparatus is materially simplified, for it is necessary only to guide the optical projection system 76a and if necessary an image frame over the image surface. This image frame will preferably be of such length that it will cover the images not yet 40 utilized as well as those already projected in common, from among the illuminated individual images of the radial image series during the operation, in order to avoid the extra light which otherwise would be emitted outwardly and create 45 interference. In order to facilitate the application of the manipulating operating system 76a upon the image disk 90, the diaphragm or a part of the same is preferably made so as to be readily removable; it may, for example, be placeable 50 upon a wide ring or the like located around the projection objective 76a.

It is, of course, also possible with opaque image spiral record disks to arrange the previously mentioned illuminating device above the image disk or to direct the light by mirrors or the like, in such manner that an image illumination takes place by means of reflected light, whereby likewise the projection objective constitutes the only 55 reproducer element which needs to be shifted.

If the cinematograph images lying in a radial series are arranged in an arcuate curved line then the optical projection system 76a may be mounted upon a swinging arm. Then preferably the luminous tube 76 may likewise be given 65 an arcuate curved shape, so that the image through the cylindrical lens optical system 91 is also curved and corresponds to the curvature of the radial series of images.

It is also possible to provide a plurality of 70 luminous tubes connected in parallel which may have vari-colored light emissions, for example, in complementary colors, for the colored projection of the images or for obtaining a mixed color. These luminous tubes may also be arranged in 75

wreath-configuration about the geometrical axis of an optical projection system, which receives the rays from the images which are to be projected. Preferably in that case the axes of the 5 optical lamp systems directed upon the images will have the same inclination with respect to the axis of the central optical system.

It may be noted further that the adjustment of the image strip need no longer occur through 10 a complicated picture screen shifting, but in simple manner for example by spatial shifting of the stator of a generator serving for producing the control potentials, or of the driving synchronous motor, or also by changing the constants of 15 the tripping of the condenser in such manner that the relative instant of time of the flash of light changes.

In Fig. 7 there is shown a projecting and reproducing device, in accordance with the invention, 20 for pictures and sounds, with separate sound and image disks. Herein 91 is a sound record of ordinary commercial type, which is traversed by a sound box 93 secured to a swinging arm 92. The sound manipulation may hereby preferably 25 be accomplished electrically and in the customary way connections may be provided for an amplifier or for a radio receiver. Around the sound record 91, but structurally separate therefrom, is arranged the image disk 94, which is here constructed 30 as an annular disk and preferably rotates at lower speed than the sound record. At its inner edge or outer edge 99 there is provided an inscription stating the contents of the image disk.

Upon a guide rail 95 which is removable by 35 means of a handle 98 from the image disk 94, or if preferred is capable of swinging out of the way, there is, preferably by means of ball bearings, roller bearings or the like, slidably arranged an image selector housing 96, which encloses 40 in a spiral groove 100 of the image disk by means of a drive pin 101. The projection of the picture upon a surface arranged at a suitable location is accomplished preferably by means of a mirror 97 which is adjustable in all 45 directions. For this purpose, for example, use may be made of the sound outlet of a loud speaker which is surrounded with a projection screen, and which is set up at some distance and reproduces the sound received from the sound 50 record 91 in synchronism with the picture.

Of course the projecting and reproducing apparatus, particularly with purely mechanical-acoustic sound reproduction, may, for example, also be provided with a structure which contains 55 a sound guide for the sound reproduced from the record 91. Through this sound guide may pass simultaneously the rays projected from the image projector 96, if necessary by means of a plurality of mirrors, whereby the light falls upon 60 a projection surface which is transparent to sound, upon which the projected image appears.

Preferably the electrical connections leading 65 to the image projector 96 are so connected with one another in known manner by means of a tube 102 that the connections are capable of following elastically every movement of the picture projector 96. The projecting device is connected to the light system by means of a connection 103. The shifting movement of the 70 image projector 96, may, for example, be assisted by a radially acting force, for example, by means of a spring or the like in a manner similar to that of Fig. 3.

In place of the slide rail 95 and the spiral guide 75 100 and 101 a screw spindle which is not axially

shiftable may also be used, upon which the picture projector 96 is secured by means of a female thread. In similar manner the portion having said female thread may be capable of being lifted off in order to provide a rapid return of the 5 picture projector to its initial position.

Fig. 8 shows the construction of the driving means for the projecting device according to Fig. 7, arranged in the housing 104.

Upon a shaft 105, which is driven by a motor 10 or other suitable means not illustrated, are secured two gear wheels 106, 107 of different sizes, which are in engagement with the toothed gears which are provided upon the two concentric shafts 108 and 109. The shaft 108 drives the 15 sound record turn table 110 and the hollow shaft 109 drives the image disk turn table 111. Because of the difference in diameter of the gear wheels 106 and 107, the two turn tables 110 and 111, and with them the sound record 91 and the 20 image record 94, will rotate at different speeds.

Instead of connecting the two turn tables 110 and 111 mechanically with one another, they may also be driven independently each through a special synchronous motor. These two synchronous motors are then connected together 25 solely electrically, in that, for example, they are operated from the same alternating current supply system. These two motors, however, have different numbers of poles, because the image 30 disk is to turn more slowly than the sound record. In the example according to Figs. 7 and 8 the image disk turn table may also be driven from its periphery, as by gears, etc.

In Fig. 9 the image reproducer 96 of Fig. 7 35 is shown on an enlarged scale. The shaded surface 112 here represents the bottom surface of the image projector and is seen slantwise from below. The carrier pin 101 and the securing elements of the portion 96 as well as the mirror 97 40 have been omitted from the drawing for greater clearness.

In the image projector housing 96 there is located also the luminous tube 113 which may for example be constructed like the luminous tube 45 6, 9 of Fig. 3. Further the housing 96 contains the condenser 114 which discharges through the luminous tube 113 at definite time intervals. The condenser 114 obtains its charge through the two conductors 116, while through the two conductors 115 synchronizing impulses are conveyed 50 to the luminous tube 113. The connections therein, for example, may be the same as those of Fig. 6. The double conductors 115 and 116 are combined outside the housing 96 in a tube 102 55 which terminates in the mechanism housing 104 of Fig. 7. For greater clearness the connecting conductors between the luminous tube 113 and the condenser 114 are not illustrated. Since long conductors between the luminous tube and the 60 condenser, aside from other disadvantages, might be particularly objectionable because by their inductance and their resistance they would prolong the duration of the individual flashes of light and might in this way injure the quality of 65 the image, it is important to keep these connections as short as possible. By combining the luminous tube 113 and the condenser 114 in a small housing very short connecting conductors 70 between these two parts are made possible, so that the briefest practicable condenser discharge is available. The light radiated from the luminous tube 113 is thrown through an optical condensing system 117 in the direction of the arrow drawn upon the image disk 94 of Fig. 7 and 75 118.

from the same is reflected upon an optical projection system 119 which is adjustable by means of a regulating knob 118.

Fig. 10 shows a further example of a projection device in accordance with the invention. Here the luminous tube 120 is arranged within a swinging arm 121 which may, for example, consist of insulating material or be lined with insulation. Within the arm 121 there are housed also other projector elements. The condenser 122, a rectifier, etc., may also be secured to the swinging arm, upon the same, at its side, or upon its bottom. The luminous tube 120 may also in special cases be arranged at an incline in the swinging arm 121. Obviously the luminous tube must be optically covered, up to the light exit opening. In order, however, to make it possible, if desired, to illuminate the entire image disk, for example in order to locate a certain point thereon for the purpose of still projection, it may be preferable to be able to open the light shielding of the tube 120 to such extent that the entire image disk, or at least a considerable part of the image record, becomes visible. Preferably for this purpose a light shutter 126a, which may be readily opened, is provided in the swinging arm 121.

The condenser 122 feeding the luminous tube 120 is here arranged in the vertical axis of swing of the arm 121, which also contains the connections including the conductors 123 for charging the condenser and the conductors 124 which supply the synchronizing impulses for the luminous tube. 122a are the connecting conductors between the condenser 122 and the luminous tube 120. The connection in this example is the same as in the example according to Fig. 6.

The light radiated from the luminous tube 120 here falls, through an optical condenser 125 and a mirror 126, upon the image spiral 127 which is provided upon a transparent plate 128. By means of a projection objective 129 the light passing through the images falls by means of a mirror 130 upon a projection screen arranged at a suitable location. The projection objective 129 and the mirror 130 are here so secured to the lower tine 121a of the fork-like swinging arm 121 that the arms 121a partakes of all the horizontal movements of the arm 121. The light source and the projection objective thus always stand exactly opposite one another. The upper tine 121 of this swinging fork may be swung back to the extent of about 180°, in order that the luminous tube 120 may be readily replaced when necessary. The positive shifting of the swinging fork 121, 121a here again takes place by means of a guide pin 131 which travels in a spiral groove 132 extending adjacent the image spirals 127. The image disk 128 rests upon a transparent turn table 133, which in turn is driven from its central axis 134. The swinging fork is preferably movable in ball bearings 135.

Fig. 11 shows in section an image arm for a projecting device such as shown in Fig. 12. The luminous tube 136 is here arranged stationary in the vertical pivot 149 of the swinging arm 137 and has the two electrodes 139 and 140 between which takes place the main discharge, fed from a condenser. 139 is, for example, a mercury electrode. In this example also an electrical connection can be provided such as shown in Fig. 6. According thereto the luminous tube 136 has a starting electrode 141 which corresponds to the starting electrode 87 in Fig. 6. To 75 this starting electrode are conveyed the start-

ing-voltage impulses which initiate the discharge of the condenser. The condenser as well as the remaining connecting elements may be stationarily arranged within the housing 138.

The light radiation of the luminous tube 136 here takes place in an axial direction, namely, vertically upwards. In front of the luminous tube 136 is arranged a small window frame 144a upon which is concentrated by means of the optical condenser 144 the light radiated axially from the luminous tube 136. By means of the lens system 144b an image of the frame opening 144a is thrown upon the image disk 151 through the mirror, prism, or the like mounted in the vertical axis of rotation of the swinging arm 137, from which (image) the light is thrown back upon the adjustable projection objective 146. This projection objective is arranged in the head of the swinging arm 137 and sends the light to a further mirror 147 which is adjustable in all directions, which throws the picture upon the projection surface. An interchangeable guide pin 148 here again serves for guiding the arm 137 upon the image disk 151. The swinging arm pivot 149 is rotatable in a guide ring and is there held tight by a bail which is secured by means of a readily releasable screw 150. After release of the screw 150 the swinging arm may be so lifted upwardly that the luminous tube 136 is readily accessible for replacement. The upper end of the luminous tube is so bent that the electrode 140 lies outside of the central axis of said luminous tube.

In the projecting and reproducing device according to Fig. 12 there are provided two rotating turn tables revolving at different speeds and connected with one another, which preferably lie adjacent one another upon a common work table, one of which serves for the image projection and the other for the sound reproduction. The image disk is here designated by reference character 151 and is provided with the spirally arranged images 152 which are received by the swingable image arm 137 (corresponding to Fig. 11). 153 designates the sound record which may be an ordinary commercial phonograph record, and which cooperates with the receiving box 154. The sound record 153 and the image record 151 are connected to one another at a positive ratio of conversion by a suitable drive gear. The sound may be amplified in a well known manner by a radio receiver amplifier and may be fed to a loud speaker which simultaneously may carry the projection screen for the images produced from the image disk 151. The loud speaker may also in a known manner be built into the radio receiver serving as the amplifier.

The sound record 153 as well as the image spiral disk 151 may be provided with synchronous starting point marks, for example with numbers or other indications. Similar indications, for example such of similar color, may also simultaneously be located at a number of points of the image and sound record in order to make it easy to locate definite synchronous points on the disks, which may be of importance in repeating a portion of the reproduction.

Fig. 13 shows a projecting and reproducing means wherein the two turn tables are arranged fixedly one above the other.

A motor 155 here through a gear drive actuates a shaft 157, upon which two further gear wheels 158 and 159 are secured. The gear wheels, through further gears 160 and 161, drive the 75

image shaft 162 and the sound shaft 163, upon which are provided the image turn table 164 and the sound turn table 165. These two turn tables here run at different speeds, namely, the sound record more rapidly than the image record.

Instead of the conversion gearing, it is also possible to provide special synchronous driving motors for the two turn tables 165 and 164, which have different numbers of poles, which, however, are both fed from the same alternating current supply system. Both motors are then preferably started at the same time by a common starting device. One or both turn tables 165 and 164 may be, in known way, mounted or driven from the 15 periphery instead of from the center.

The entire mechanism is arranged in a housing 166, whose upper portion 167 swings open upwardly and which, furthermore, has a lateral door 168. The sound record 165a resting upon the 20 turn table 165 is reproduced by means of an electrical reproducer box 169 secured to a swinging arm 180, while the image plate 164a which rests upon the turn table 164 and has the picture spiral series 170, is projected by means of the device 25 series 170 hereinafter described.

On the free end of a swinging arm 171 whose said free end is turnable upward about a hinge 171a, are arranged two luminous tubes 172 and 173 which are fed from a condenser 174 in the 30 manner already described. This condenser 174 is arranged in the interior of the hollow space of the swinging arm. The luminous tubes 172 and 173 radiate the light in an axial direction and through the optical condensers 175 and 176 illuminate the individual images of the series of 35 image spirals 170. Through a centrally arranged projection objective 177 and through a mirror or prism 178 the images are projected through a preferably glazed opening 179 which is provided 40 in the wall of the housing 168, and projected upon the screen and preferably upon a radio loud speaker provided with a projection surface, which simultaneously and synchronously with the picture projection, reproduces also the sounds received from the electric box 169 and amplified. In or on the described radially moving or swinging arms light transporting agencies may be provided for example in the form of round or rectangular glass light-conducting rods or cones.

It is desirable for preventing disturbances to 50 make use of the known screening means and particularly to surround the condenser tripping device as well as the luminous tube together with its connections as far as possible with a grounded 55 metallic shield. When using optical reproduction of sound, particularly in such cases where the sound record is located upon the image disk, for example, parallel to the image spirals, it is further important to shield the sound record and the 60 photo-electric cell which reproduces the same carefully against the intermittent light of the luminous tube serving as the source of projection light. On the other hand it is advantageous to 65 keep the light of a constant light source serving for producing the synchronizing impulses away from the luminous tube serving as the source of projection light, in order for example to prevent influencing the cathode of the luminous tube as to the ignition frequency in an undesired manner 70 by photo-electric effect.

Furthermore, a switch which shuts off the charging current of the condenser may be so arranged and constructed that simultaneously with the disconnecting of the charging current 75 it connects a resistance in parallel with the con-

denser, whereby any chance residual charges of the condenser may discharge through the resistance in order that—for example, in interchanging the luminous tubes—the hand of the operator may be protected from danger of shock. 5

The above described examples of embodiments show only a few of the numerous possibilities of construction. The drawings are throughout to be considered only as diagrammatic sketches and not as correct in scale and detail, and must rather 10 be considered to serve only for explaining the most important features and a few structural arrangements of the device in accordance with the invention. Essential devices, which, however, are less important details for understanding the 15 characteristics of the invention have been entirely omitted or designated by simplified symbols in order to facilitate the understanding of the invention.

I claim:

1. A combined sound reproducing device and projection device for continuously rotating cinematogram disks carrying spirally arranged transparent image records, said combined device comprising optical means for projecting the cinematographic images, an image-illuminating device which consists of at least one luminous discharge tube, an electrical condenser, means for charging same, and means whereby said condenser is rapidly discharged through said tube to produce flashes of light, to illuminate said image records, said device including a shiftable two-armed fork, one arm thereof being arranged on one side of the image disk and carrying the illuminating device while the other arm, arranged on the other side of the image plate, carries the optical projection system, the arm above the image disk being constructed to fold upward to facilitate changing the image disks. 20

2. A combined sound reproducing device and projection device for continuously rotating cinematogram disks carrying spirally arranged image records, said combined device comprising optical means for projecting the cinematographic images, an image-illuminating device which consists of at least one luminous discharge tube, an electrical condenser, means for charging same, and means whereby said condenser is rapidly discharged through said tube to produce flashes of light, to illuminate said image records, the spirally arranged images being spaced at equal angular distances from one another with respect to the axis of the disk whereby they thus lie in radial series, the illuminating means being disposed so as to illuminate an entire radial series of the images in common at any instant, and means whereby only a single image of such series is actually projected at any given instant. 45

3. A combined sound reproducing device and projection device for continuously rotating cinematogram disks carrying spirally arranged image records, said combined device comprising optical means for projecting the cinematographic images, an image-illuminating device which consists of at least one luminous discharge tube, an electrical condenser, means for charging same, and means whereby said condenser is rapidly discharged through said tube to produce flashes of light, to illuminate said image records, the spirally arranged images being spaced at equal angular 60 distances from one another with respect to the axis of the disk whereby they thus lie in radial series, the illuminating means including a cylindrical lens arranged between the luminous tube and the image disk and disposed so as to illum- 65 70 75 80 85 90 95 98

nate an entire radial series of the images in common at any instant, and means whereby only a single image of such series is actually projected at any given instant.

- 5 4. A combined sound reproducing device and projection device for continuously rotating cinematogram disks carrying spirally arranged image records, said combined device comprising optical means for projecting the cinematographic images, an image-illuminating device which consists of at least one luminous discharge tube, an electrical condenser, means for charging same, and means whereby said condenser is rapidly discharged through said tube to produce flashes

of light, to illuminate said image records, the spirally arranged images being spaced at equal angular distances from one another with respect to the axis of the disk whereby they thus lie in radial series, the illuminating means being stationary and disposed so as to illuminate an entire radial series of the images in common at any instant, the device having also a radially shiftable optical projection system, structurally separate from the illuminating means, whereby only 10 a single image of such series is actually projected at any given instant.

RUDOLF LEVY.
